WORK FEEDING DEVICE

James R. Townley, Chamois, and Anthony J. Mauntel, Washington, Mo., assignors to Judson L. Thomson Mfg. Co., Inc., Waltham, Mass., a corporation of Massachusetts

Application June 15, 1935, Serial No. 26,756

10 Claims. (Cl. 218—17)

This invention relates to a work feeding device which, although designed primarily for use in machines for setting lacing hooks of the general character shown and described in United States Letters Patent No. 977,090, issued to Arthur R. Havener on November 29, 1910, is yet capable of application to various other machines. In machines of the above character, the work in which the lacing hooks are set is generally fed the required distance between hooks by the setting tool after each clenching operation. The tool is provided with a punch portion and an annular setting shoulder and, after the setting operation, the punch portion remains in the bore of the hook and serves as positive means for feeding the work.

In lacing studs, however, the bore in the shank or barrel of the stud does not open out through the body of the stud but is closed at its inner end, so that, when the machine is used for setting lacing studs, a tool having an annular setting shoulder with a central slightly protruding boss or pilot and no punch portion is substituted in the machine for the hook setting tool. Considerable difficulty in feeding the work has been experienced in the use of such machines for setting lacing studs because the central cavity in the clenched end of the stud is so shallow that the setting tool, when moved laterally to feed the work, frequently slips out of said cavity and fails to feed the work the required distance in consequence of which the studs are unevenly spaced. This results in defective work which cannot be repaired and is a material loss.

The main object of the present invention is the provision in machines of the general character described, of means for positively insuring an exact and accurate feeding of the work.

Another object of the invention is the provision in a machine such as a lacing hook machine of feeding means adapted to be controlled by and in unison with the movements of the setting tool. A further object is the provision of a feeding device which will neither mar nor deface the work.

Other objects of the invention will be in part obvious and in part described hereinafter.

Our invention contemplates the provision of two members between which the work is clamped, one of said members being in the nature of a slide adapted to support the work and the other in the form of a clamp to hold the work against the slide. When in clamped position the two members are moved as a unit to feed the work.

When our invention is applied to a lacing hook

machine, the movements of the two members of the feeding device are preferably controlled by the movements of the setting tool so that when that member descends to effect the clenching of a lacing stud, the clamp descends to clamp the work and on the lateral movement of the setting tool, the clamp and slide are moved in unison therewith to feed the work. At the conclusion of the feeding movement, the setting tool and feed members return to their initial positions, the work meanwhile being held by the usual presser foot.

In the accompanying drawings illustrating our invention, Figure 1 is a front elevation as viewed from the operator's seat of a portion of a machine for setting lacing hooks of the general construction disclosed in the patent hereinbefore referred to and shown as having applied thereto a work feeding mechanism constructed and adapted to be operated in accordance with our invention;

Fig. 2 is a side elevation, looking from left to right, in Figure 1, of the central portion of the parts shown in said figure;

Fig. 3 is a horizontal sectional view on line 3—3 in Figure 1, looking downwardly; and

Fig. 4 is a vertical sectional view on line 4—4 in Fig. 3.

In the drawings, the parts shown of the machine of said patent are, for the sake of clearness, given the same reference numerals as in said patent.

Referring to those parts of the machine of the patent hereinbefore referred to which are shown in the drawings, 29 indicates the frame of the machine and 27 a work support made in two parts 29 and 30. The part 30 of the work support 27 is a plate which is fastened in position by screws and extends around and abuts against the upper portion of the part 29 to form a flat surface upon which the work is placed. The work is clamped to the work support by means of a presser foot 35 adjustably fastened to the upper end of a rod 41 and means (not shown) is provided for raising the presser foot during the operation of the machine to permit the work to be fed. Treadle operated means (not shown) is also provided which permits the operator to raise the presser foot for inserting or removing work.

In place of the usual punch for setting lacing hooks which is shown in the said patent, we show a setting member without the punch portion which is adapted for setting lacing studs. This tool comprises a setting or clenching shoulder 49 formed upon the lower end of a stud 50, against which shoulder the shank of the lacing stud 55

- strikes to clench the same during the setting operation. The stud 50 is screw threaded into a slide 52 mounted for horizontal reciprocation to feed the work upon tubes 53, 53, which are fastened to a plunger 54 which, in turn, is arranged for vertical reciprocation in bearings 55 in the frame 20 to move the stud 50 into and out of setting position.
- A sliding movement is imparted to the slide 52 from a rock shaft (not shown) through a link 72 pivotally connected at one end to said slide and at its other end mounted on a pin 74 fastened in a yoked arm 76 which in turn is fastened to said rock shaft.
- A die plate 87 provided with a hole 98 is designed to cooperate with a punch when it is substituted for the setting tool 50, which die plate is fastened to a slide 99 adapted to be reciprocated at the proper time into and out of alignment with the punch by a lever 100 pivoted to the frame 20 at 103 and connected by a link 104 to a lacing hook or lacing stud carrier slide (not shown) mounted for reciprocation.
- The lacing studs are fed from a hopper (not shown) into a raceway 107 and thence pushed through an auxiliary raceway 114 onto a lacing stud carrier plate 116 by means of a lever 117. The lacing hook carrier 105 includes a lever 127 having fastened to its upper end the carrier plate 116.
- For a fuller description of the parts of said machine and the mode of operation of the machine, reference may be made to the said patent hereinbefore mentioned.
- The work feeding device of our invention comprises a slide 209 adapted to support the work and mounted for horizontal reciprocation and a clamp 201 mounted for vertical reciprocation into and out of a position of clamping the work to said slide. In applying a device constructed in accordance with our invention to a machine of the patent referred to, the work support 29 is recessed longitudinally and in the direction of the feed of the work to form a guideway 204 in which is slidably mounted the slide 209. This member is of rectangular form having a longitudinal centrally located channel or groove 205 opening out both ends of the slide to accommodate the portions of the lacing studs which project downwardly from the front face of the work.
- The clamp 201 is provided with a stem 207 slidably mounted in a cylindrical housing 208 provided with a closed but bored end through which projects a pin 209 set in the upper end of the stem. The projecting end of the pin 209 is threaded to receive a nut 210 and a set nut 211 for limiting the downward movement of the clamp in its housing and a helical spring 212 mounted on the pin 209 within the housing 208 and under compression forces the clamp downwardly yet permits it to yield to exert a resilient pressure on the work when in clamping position. That portion of the stem 207 adjacent the clamp 201 may be enlarged at 214, thus providing an annular shoulder at its upper end adapted to engage the lower end of the housing 208 to limit the upward movement of the clamp in the housing.
- For imparting the appropriate movements to the clamp to engage the work and feed it, the clamp is mounted to move with the slide 52, which has both a vertical and a horizontal reciprocation. Any suitable means may be provided for this purpose and one such means is shown comprising a yoke bracket 216 which is approxi-

mately U-shaped, and is fastened in a sidewise position to the slide 52. For this purpose, the upper arm 217 of the bracket is provided with a hole in its end so that it may be mounted upon the setting tool 50 and fastened in fixed position to the lower portion of the slide 52 by a nut 218 threaded on the setting tool 50. The upper arm 217 is curved so that the head of the bracket is located back of the work support and its lower arm 219 is turned in under the work support and is bored to fit slidably a depending stud 220 (Fig. 4) having a threaded portion 221 which is screwed into the bottom of the slide 200, the work support being provided with a slot 223 to permit movement of the stud with the slide 200. The stud may be provided with a collar portion 225 adapted to engage the under surface of the work support to hold the slide within the guideway 204.

The clamping member is mounted in the upper arm of the bracket adjacent the setting tool, the bracket being bored to receive the cylindrical housing 208 which is held therein in adjusted position by two nuts 227 and 228, threaded on the outer surface of the housing, which engage opposite faces of said arm 217.

Preferably, the bracket is made of two right-angled parts held together by two screws 230 threaded into one of said parts, the other of said parts being provided with slots 231 permitting the space between the two arms of the bracket to be varied within certain limits.

The operation of our device is as follows: In the operation of the machine, the presser foot is raised to permit insertion of the work face 35 down and when it has been properly positioned on the work support, the presser foot is dropped. The starting of the machine then causes the slide 52 and setting tool 50 to move downwardly and the lacing stud carrier to move upwardly carrying a lacing stud which has been presented to it from the raceway and the shank of the stud is forced through the work and clenched upon the wrong side of the work by the clenching shoulder on the setting tool. The setting tool then releases slightly and the slide 52 is reciprocated to the left, as shown in Figure 1, to feed the work.

When the slide moves downwardly to bring the setting tool in clenching position, the clamping member is carried downwardly with the bracket 50 and the clamp 201 engages the work to clamp it to the face portions of the slide on both sides of the channel, the pressing face of the clamp being of sufficient width to overlap these portions. The clamp is so adjusted as to engage the work just before the setting tool reaches clenching position so that further downward movement of the clenching tool results in the spring backing up, the clamp being slightly compressed so that the clamp exerts a resilient pressure on the work to clamp it to the slide 200. In this downward movement, the lower arm of the bracket moves downwardly on the stud 220 set in the bottom of the slide.

When the slide 52 is moved to the left, the clamp 201 and the slide 200 are moved as a unit the required distance to feed the work, the presser foot during this operation being in a raised position for releasing the work. At the end of the feeding movement, the presser foot automatically descends and holds the work and the slide 52 moves upwardly withdrawing the setting tool and the clamp from the work and then moves to the right to the initial starting position.

Although we have shown our feeding device as

being used on a machine for setting lacing studs, it may be found of value for feeding the work when that machine is used with a tool having a punch portion for setting lacing hooks, especially where the work in which the lacing hooks are being set is of very thin material. Our device is not to be limited, however, to use in machines of the character described, because it is susceptible of use in various other machines where an accurate feed is desired without subjecting the material to the possibility of stretching. It is also to be understood that our invention is not to be limited to the form of construction herein shown and described, since it may be embodied in other forms within the scope of the following claims.

What we claim is:—

1. A device of the character described comprising a work supporting slide, a yoke bracket, a clamp mounted in said bracket, said bracket being slidably connected at one end to said slide, and means for moving said bracket vertically to apply said clamp to the work on said slide and then horizontally to move said clamp and said slide in unison to feed the work.
2. A device of the character described comprising a work supporting slide, a yoke bracket, a clamp mounted in said bracket, said bracket being connected at its lower end to said slide permitting relative movement between the two in a vertical direction, and means for moving said bracket vertically to apply said clamp to the work on said slide and then horizontally to move said clamp and said slide in unison to feed the work.
3. A device of the character described comprising a work supporting slide, a yoke bracket, a resilient clamp mounted in said bracket, said bracket being slidably connected at one end to said slide, and means for moving said bracket vertically to apply said clamp to the work on said slide and then horizontally to move said clamp and said slide in unison to feed the work.
4. A device of the character described comprising a work-supporting slide provided with a vertical stud and mounted for horizontal reciprocation, a clamp-carrying member, said member having one end slidably mounted on said stud permitting relative movement between said member and said slide in a vertical direction but not in a horizontal direction, a clamp mounted on said member and means for moving said member vertically to apply said clamp to work on said slide and then horizontally to move said clamp and said slide in unison to feed the work.
5. The combination of a tool-carrying member mounted for vertical and horizontal reciprocation, a work-supporting slide mounted for horizontal reciprocation, a clamp-carrying member fastened to said tool-carrying member for movement therewith, said clamp-carrying member being so connected to said slide as to permit relative movement between said clamp-carrying member and said slide in a vertical direction but not in a horizontal direction, a clamp mounted on said clamp-carrying member and means for moving said tool-carrying member vertically to apply said clamp to work on said slide and then horizontally to move said clamp and said slide in unison to feed the work.
6. The combination with a tool-carrying mem-

ber mounted for vertical and horizontal reciprocation, a tool carried by said member and means for moving said member vertically to cause said tool to operate on the work, and then horizontally, of a work-supporting slide mounted for horizontal reciprocation, a clamp-carrying member fastened to said tool-carrying member for movement therewith, said clamp-carrying member being so connected to said slide as to permit relative movement between said clamp-carrying member and said slide in a vertical direction but not in a horizontal direction, a clamp mounted on said clamp-carrying member for clamping the work to said slide when said tool-carrying member is moved downwardly to cause said tool to operate upon the work, said clamp and said slide being adapted to move in unison to feed the work when said tool-carrying member is moved horizontally.

7. The combination with a tool-carrying member mounted for vertical and horizontal reciprocation, a tool carried by said member and means for moving said member vertically to cause said tool to operate on the work, and then horizontally, of a work-supporting slide mounted for horizontal reciprocation, a yoke bracket fastened to said tool-carrying member for movement therewith, said yoke bracket being so connected to said slide as to permit relative movement between said bracket and said slide in a vertical direction but not in a horizontal direction, a clamp mounted on said bracket for clamping the work to said slide when said tool-carrying member is moved downwardly to cause said tool to operate upon the work, said clamp and said slide being adapted to move in unison to feed the work when said tool-carrying member is moved horizontally.

8. The combination of a tool-carrying member mounted for vertical and horizontal reciprocation, a work-supporting slide mounted for horizontal reciprocation only, means mounted on said member for moving said slide horizontally in unison with the horizontal movement of said member and means carried by said slide-moving means for clamping work to said slide when said member is moved downwardly.

9. The combination of a tool-carrying member mounted for vertical and horizontal reciprocation, a work-supporting slide mounted for horizontal reciprocation only, said slide having a longitudinal groove to accommodate projecting portions of the work, means mounted on said member for moving said slide horizontally in unison with the horizontal movement of said member and a spring-pressed clamp for clamping work to said slide when said member is moved downwardly.

10. The combination of a tool-carrying member mounted for vertical and horizontal reciprocation, a tool mounted in said member, a work-supporting slide mounted for horizontal reciprocation only, means mounted on said member and slidably connected to said slide for moving said slide horizontally in unison with the horizontal movement of said member, and a clamp carried by said slide-moving means in advance of said tool for clamping work to said slide when said member is moved downwardly.
